RELAXING BENCH

Lee E. Carlile, San Francisco, Calif.

Application January 15, 1944, Serial No. 518,463

4 Claims.

(Cl. 5—62)

This invention relates to a relaxing bench useful in posture correction, as a health aid and as a beauty aid.

It has long been recognized that very considerable benefit could be gained if a person would recline for even a short period of time on a firm, flat surface. Additional benefits are frequently gained if the support is tilted; in some cases it is desirable that the head be raised while in others the feet should be uppermost. The device of the present invention is adapted to these several uses. In addition, it is characterized by its simplicity of construction and ruggedness. Further, it is so fashioned that it can be manipulated by one reclining upon its table; this makes it unnecessary for a person to rise from the table to change it to another position.

It is a broad object of the present invention to provide a novel relaxing bench.

Another object of this invention is to provide a relaxing bench having a table which can be manipulated by a person reclining thereon to a selected position.

The invention includes other objects and features of advantage some of which, together with the foregoing, will appear hereinafter wherein a preferred form of relaxing bench is disclosed. In the drawings accompanying and forming a part hereof, Figure 1 is a plan view of the bench. Figures 2, 3 and 4 are side elevations showing the table in various positions. Figures 5 and 6 are respectively sectional views along the lines 5—5 and 6—6 of Figure 2.

The relaxing bench includes a base generally indicated by numeral 6. The base includes a pair of side rails 7 supported on corner legs 8 and spaced apart and braced by transverse members 9. Each side rail is generally triangular in outline, the upper side of each rail having adjacent portions 11 and 12 sloping upwardly toward the mid-point 13 of each rail.

A table 14 is provided on which a person can recline, the table being made up of several members joined together to provide a flat surface on which a person can recline; it has a head 15 and a foot 16. If desired, the table can be upholstered or covered with some type of cover or mattress.

Means are provided for supporting the table on the base in any one of three selected positions and for moving the table between these positions. The three positions are as follows:

- (1) A horizontal position.
- (2) A first tilted position in which the head

end is down and the foot end is uppermost and above the horizontal.

(3) A second tilted position in which the foot end is down and the head end is raised above the horizontal.

To support the table in a horizontal position I provide a first support 16 adjacent the head end. This is supported by hinges 17 on one of the transverse members. It can be readily released and moved into its non-support position shown in Figures 3 and 4. A second support 18 is supported on hinges 19 on another transverse member 9. This support is also movable by a person on the table between its support position (Figure 2) and its non-support position (Figures 3 and 4). To effect this I provide lever 21 having one end pivoted at 22 on one of the side rails. The other end of the lever extends beyond the other side rail and is movable in a slot 23. The slot includes a portion 24 which locks lever 21 in a position in which the support 18 is in support position (Figure 2); when lever 21 is released from portion 24 the support 18 is moved into its non-support position of Figures 3 and 4. A link 26 extends between the lever 21 and one end of the centrally pivoted lever 27, the other end of which is connected by link 28 to the support so lever 21 can manipulate the support.

When both supports 16 and 18 are raised into that position in which they appear in Figure 2, the table is stably supported in a horizontal position. When the supports are lowered the table can be selectively tilted by manipulating levers 31. One of these is pivoted on each side rail at a point whereat a person on the table can manipulate them. Each lever 31 has a handle portion 32 formed on the end thereof.

To tilt the table selectively, a frame, generally indicated by numeral 33, is hinged on opposite legs of the base. A roller 34 is carried centrally of the frame and runs in a guide or track 35 at the foot of the table. The frame is moved by links 37 which connect the frame to each lever 31. The end of each link 37 is slotted at 38 to engage a pin 39 carried by the frame. The slot 38 permits levers 31 to remain in a position convenient to a person on the table no matter which of the three positions the table occupies at any given adjustment. Positive engagement with the slot and pin 39 is secured by having the slot include a vertical portion 41 to receive the pin.

In Figures 2, 3 and 4 I have shown the three positions which the table can occupy. In Fig-

ure 2, both supports 16 and 18 are engaged with the table and levers 31 are disengaged, pins 39 merely riding in the slots 38. If lever 21 is released from notch 24 and support 16 is lowered the table can be tilted selectively by first raising levers 31 to engage pins 39 and vertical slot portions 41. Then the tilting frame can be rocked counter-clockwise to the position of Figure 3 or clockwise to the position of Figure 4. If it be desired to move the table into a horizontal position it is only necessary to move levers 31 until the table is horizontal whereupon supports 16 and 18 are moved into place.

The device can be readily fashioned of wood, metal or a combination of these. It is simple, rugged and inexpensive. Within the scope of the claims various equivalent modifications will suggest themselves to those skilled in the art.

I claim:

1. A tiltable couch comprising a table having a head and a foot, a base including opposite side rails extending beneath and longitudinally of said table, a first support for engaging the underside of said table adjacent one end thereof when the table is in a horizontal position, means hingedly supporting said first support at one end of said base, a second support for engaging the underside of said table adjacent the other end thereof when the table is in a horizontal position, means hingedly supporting said second support at the other end of said base, means for moving one of said supports between a table support position and a non-support position, a tilting member pivotally mounted on said base and engaged with an end of said table for moving said table between a first position in which said table is tilted with said head above the foot and a second position in which said table is tilted with said head below the foot, means for moving said tilting member including a lever mounted on each side rail of said base adjacent the head thereof, a link extending along each side of said side rails and directly connecting said lever to said tilting member whereby said member can be selectively manipulated, and a pin and slot connection between said tilting member and each link for rendering said moving means ineffective to move said table until said second support is released from engagement with said table.

2. A tiltable couch comprising a table having a head and a foot, a base including opposite side rails extending beneath and longitudinally of

said table, a tilting member pivotally mounted on said base and engaged with an end of said table for moving said table between a first position in which said table is substantially level and a second position in which said table is tilted with said one end below the other end thereof, and means for moving said tilting member including a lever mounted on each side rail of said base adjacent said one end thereof, a link extended between said lever and said tilting member, a pin on said tilting member, and an L-shaped slot in an end of said lever and engaged with said pin whereby said tilting member can be selectively manipulated and locked in table-tilting position.

3. A tiltable couch comprising a table having a head and a foot, a base including opposite side rails extending longitudinally beneath said table, the upper side of each side rail having a portion sloping upwardly from said head to the middle of the rail, a tilting member pivotally mounted on said base and engaged with an end of said table for moving said table between a first position in which said table is level and a second position in which said table is tilted with said head below the foot and said table is supported on said sloping rail portions and said tilting member, means for moving said tilting member including a lever mounted on said base adjacent the head end of said table and a link connecting said lever to said tilting member whereby said tilting member can be selectively manipulated.

4. A tiltable couch comprising a table having a head and a foot, a base including opposite side rails extending longitudinally beneath said table, the upper side of each side rail having a portion sloping upwardly from said head to middle of the rail, a tilting member pivotally mounted on said base and engaged with an end of said table for moving said table between a first position in which said table is level and a second position in which said table is tilted with said head below the foot and said table is supported on said sloping rail portion and said tilting member, means for moving said tilting member including a lever mounted on said base adjacent the head end of said table, a link connecting said lever to said tilting member whereby said tilting member can be selectively manipulated and a pin on said member, said link having an L-shaped slot in an end thereof and engaged with said pin.

LEE E. CARLILE.
